JAMES CAMROD LEDBETTER, OF NEW YORK, N. Y., ASSIGNOR TO THE PROSPERITY COMPANY, INC., OF SYRACUSE, NEW YORK, A CORPORATION OF NEW YORK

FLUID-PRESSURE PRESS

Application filed March 3, 1928. Serial No. 258,713.

This invention relates to power-type garment and laundry presses and more particularly to fluid-expansive motor-operated presses.

5 An object of the invention is to produce a power press wherein the motor or power producing means is carried by or within one of the press jaws and to employ a power means of simple form and small size thus producing a power press jaw of compact light weight construction.

A further object is to produce a power press for garment pressing and laundry ironing operations wherein the power producing or motor means comprises a diaphragm actuated jaw presser plate, the diaphragm motor means being disposed between the jaw and plate and being operated by the steam ordinarily used to heat the jaw and plate.

20 A further object is to produce a power press jaw which includes a presser plate having spray means by which the work is sprayed with air or steam to condition the work or garment for the pressing and finishing operation.

It is a further object to produce a press embodying a movable jaw or jaws such as a press head and buck wherein the motor means is concealed within the jaw; and control means for stopping and starting the operation of the motor means is mounted directly on the jaw, together with a spray control means similarly mounted. In this way 35 the power-press or fluid-pressure jaw is provided with two control means, one for controlling the jaw presser or compression plate and the other for controlling the steam or air spraying operation. Hence the entire 40 control of the press is effected from the press head or upper jaw.

The accompanying drawing illustrates an example of the invention serving to illustrate the principles involved, and the two views 45 show a conventional garment press or laundry ironer of the flat jaw-press type in closed position and with which my novel motor means is associated.

Figure 1 shows the upper portion of a 50 press with the lower jaw or buck in end ele-

vation and the upper jaw or head in transverse section, the section being taken through the two control means and showing the fluid-pressure actuated motor means in the form of a disk-type diaphragm.

Figure 2 shows a front view, the press head being in longitudinal section and the buck being in elevation.

The views show the diaphragm in section within the active or power jaw so that no movable parts are exposed. According to the principles of my invention, either pressing member or jaw, i. e. the head or buck, may carry the fluid-pressure actuated diaphragm. Furthermore, either the head or buck or both may be movable to open and close the press, the present invention relating in effect to a novel fluid-pressure motor means carried by or within either one of the jaw pressing members.

A press frame 5 of suitable form carries two press jaws adapted to open and close on the work and one of the jaws is usually referred to as the buck 6 since this is the lower pressing member or buck and which may be mounted stationary on the frame. The upper jaw or press head 7 is movable to open the press and is actuated by any suitable operating means. The press head 7 may be carried on a press lever 8 as operating means pivoted at 9 on the frame 5. A fluid or steam transmitting pipe 10 conveys compressed air or steam through a pipe 11 to the head jaw 7. The frame 5 and jaw operating means 8 is merely diagrammatic and may assume any desired form.

The head jaw 7 usually includes a heating chamber 14 and the pipe or pipes 11 connect at 15 to this heating chamber 14. The heating chamber 14 usually extends throughout the press head 7 so as to heat the same by steam to a suitable ironing or pressing temperature. The margin or perimeter of the press head 7 may to advantage be outlined by a downwardly extending flange 12 in which a press or pressure plate is carried for limited movement as later described and is adapted to be actuated through a short stroke to produce the necessary compression on the work placed on the buck 6.

A motor power means control device in the form of a valve 16 is mounted on the jaw 7. This valve 16 includes a valve case 17 which is anchored in the upper and lower walls 18 and 19 and is provided with a fluid pressure discharge port 20 leading from the heating chamber 14 down into a diaphragm compression chamber 21. The valve casing 17 has inlet ports 22 through which fluid pressure, air or steam, is admitted for passage from the heating chamber 14 through the valve 16 and through the port 20 into the diaphragm compression chamber 21. The control valve 16 is provided with a valve stem 23 which raises and lowers by a handle 24 against the port or seat 20 to open and close the valve and by which the movement of fluid pressure is effected from the chamber 14 to the power or compression chamber 21. The valve 16 may include an exhaust port so that fluid pressure in the chamber 21 can be discharged therefrom to relieve the jaw compression.

The press head steam heating chamber 14 may be arched or raised over the compression chamber 21 thereby affording a space within the jaw 7 and under the heating chamber 14 to form a compact small size construction, and the compression chamber 21 is defined by a circular flange or rim 26 to receive a disc-like diaphragm. The proximity of the one chamber 21 to the other 14 maintains the compression chamber 21 at a high temperature substantially equivalent to that of the heating chamber 14. Although there is shown one compression chamber 21 disposed under the press lever 8, it is evident that any suitable number of like compression chambers may be formed in the jaw 7, particularly if the latter is a rather long press head of large proportions designed for large size flat work.

A flexible metallic diaphragm 27 is corrugated in circular formation to render it inherently elastic in movement within itself so as to yield under the force of steam or air pressure admitted into the compression chamber 21. The diaphragm periphery 28 is sealed onto the flange 26 by any suitable means, as by a ring 29 and screws 30. Therefore the diaphragm 27 and the lower wall 19 form the compression chamber 21 into which steam pressure is received and expanded to actuate a pressure plate as will be explained.

A jaw presser or pressure plate including an upper solid wall 32 and lower foraminous wall 33 is carried directly underneath the jaw 7 and is relatively movable up and down within the guide flange 12 forming the outer margin of the head 7. This press plate 32-33 therefore forms a spray chamber 34 perforated at 35 to make foraminous the press plate wall 33, as heretofore mentioned. The marginal flange 12 may to advantage be included in this construction and in this flange the press plate 33 is confined for a limited down-

ward compression movement against the work on the buck 6.

The jaw 7 and press plate 33 are held together for relative motion by any suitable means, as for example by a bolt 37 anchored at 38 to the press plate 32-33 and the bolt is freely movable in an aperture 39 formed in the jaw 7. A spring or other suitable resilient means may be mounted on the bolt 37 between a nut and washer means 41 and the surface of the jaw 7. This spring construction 40 acts to normally hold together the jaw 7 and the press plate 32-33 but the spring yields under force of the diaphragm 27 to afford a slight downward movement of the press plate 33 against the work on the buck 6. Any suitable number of jaw and press plate retaining means 37-40 may be used, as for example one at each end of the press head.

The steam or fluid pressure admitted through pipes 11 and through apertures 15 into the heating chamber 14 is also admitted directly into the compression chamber 21 by pulling downwardly on the valve handle 24. In this way the valve stem 23 is lifted off the valve seat orifice 20 and steam or air flows then into the compression chamber 21 thus causing the diaphragm 27 to move downwardly which acts to slide the press plate 33 in the jaw guide 12 to produce pressure on the buck. The valve handle 24 is immediately released and the fluid pressure remains in the compression chamber 21 to hold the press plate down to produce jaw compression until after the pressing operation has actually been completed, whereupon the operator may release the jaw compression through the other control means which will now be described.

The press plate 32 is formed with a fluid passage 43 which is open at the top to communicate with the compression chamber 21 and which is closed at the bottom, but is provided near the bottom with a valve seat orifice 44 leading outwardly into the spray chamber 34 of the pressure plate 33. This valve orifice 44 is closed by a valve stem 45 which is reciprocated by a valve handle 46, and the latter parts are preferably spring actuated so as to normally maintain the valve seat 44 in closed condition. The operator may press the valve handle 46 to open the orifice 44 thereby exhausting fluid pressure from the compression chamber 21 into the spray chamber 34 and hence onto the work which relieves the expanded or bulged tension of the diaphragm 27 just at the instant the work is steam sprayed or air sprayed thereby permitting the spray medium to be impregnated in the fabric of the goods to be pressed.

There are various modes of pressing and spraying processes to which the operator may resort in the use of this press. For example he may leave the valve 45-46 normally

closed when he first closes the press head 7 down upon the work, and he may thereafter simply open the motor means control valve 16 thereby dry pressing the work since the spray control valve is not opened. In this way certain kinds of work may be dry pressed or ironed as in laundry requirements.

On the other hand, the operator may open the valve 45 thereby spraying the work after it has received a few seconds of dry pressing, or he may simultaneously open both valves 24 and 46 thereby spraying and pressing the work at one and the same time. Opening the spray valve 46 slightly and the jaw compression valve 24 fully maintains the diaphragms in extended position to effect jaw compression despite the fact that a small quantity of steam is flowing into the work. Thereafter the fluid pressure is exhausted from the diaphragm chamber 21 by any approved means, and the springs 40 then retract the pressure plate and hence compression is removed from the work on the buck.

After the pressing operation and exhaust of fluid pressure from the diaphragm chamber, the anchorage means 40, which holds together the jaw 7 and press plate 33, instantly pulls upwardly on the bolt 37 to remove the pressure plate from the work and returns the diaphragm 27 to normal non-pressing position as shown in the drawing. A pressing machine of this character is simple in construction and easy to operate and there is no exposed mechanism carried on the frame of the machine and all movable parts are concealed.

It is observed that the pressure plate fluid entry passage 43 leads through the diaphragm 27 and that the diaphragm may be sealed on the plate 32 in any suitable way as at 31. The heating chamber 14 is curved upwardly at 13 to bring the compression chamber 21 and the two sealing means 29 and 13 into alignment with the chamber 14. The valve 16 is located at the highest point of the heating chamber and therefore discharges the dryer steam held in the chamber 14 down into the spray chamber for steam-treating and moistening the work. The plate 31 is anchored by screws or other means to the wall 32 and seals the diaphragm to said wall. A screw plug 31a provides an opening through the upper walls 18 and 19 to insert and secure the plate 31 in place.

The active or power jaw 7 in its simplest form consists of a stationary part 7 and the relatively slightly movable pressure plate 32-33 which is forced downwardly to produce jaw compression by the motor means 27, the pressure plate including means to air-spray or steam-spray the work. The stationary part or member 7 includes the two chambers 21 and 14, one under the other, while the pressure member or plate 32-33 includes the one air or steam spray or suction

chamber 34. The diaphragm 27 is of the flat-circular plate or disk type and being inherently flexible and attached to both the stationary and movable member, completes the structure of the compression chamber 21 which is formed between the two main relatively movable jaw members 7 and 33.

The yielding connecting or anchorage means 40 retracts the compression plate 32-33 into close engagement with the heating chamber 14 of the other plate 19, the member 18-19 forming a support for the movable presser plate. The two complementary jaw parts or plates have their adjacent walls 19 and 32 in direct surface contact throughout the complementary area of the two cooperating relatively movable plates. Hence there is good heat conductivity from the heating chamber 14 through the wall 19 into the compression plate and spray chamber 14 to heat the working face 33 of the compression plate.

The plate 33 is well heated because of its intimate contact with the wall of the heating chamber 14 since a pressing operation is effected in a short time and thus the space which occurs between the two walls 19 and 32 during the pressing operation does not remain long enough to retard the heating of the compression plate from the heating chamber plate. Furthermore the flange 12 over hangs the plane of separation between the two walls 19 and 32 and hence air cannot circulate or blow between the two plates when the diaphragm reacts from the support and bellows out or extends itself to drive the compression plate away from the supporting member 18 to which the compression plate is attached. The flange 12 also makes for safety since the operator cannot be accidentally injured or get his work caught between the two complementary parts.

I claim as my invention:

1. A press comprising, coacting jaws and operating means to move one of the jaws to open and close the press, one of the jaws consisting of relatively movable members and means to operatively hold them together, a spray chamber formed in one of the members, a compression chamber provided between the two members and a fluid-expansive motor means disposed over the compression chamber and engaging both members, means to regulate the flow of a fluid pressure into the compression chamber to actuate the motor means and produce jaw compression, and means to admit fluid pressure from the compression chamber through the fluid-expansive motor means to the spray chamber.

2. A press comprising, coacting jaws and operating means to move one of the jaws to open and close the press, one of the jaws consisting of two relatively movable members and resilient means to operatively hold them together, a spray chamber formed in

one of the members, a compression chamber provided between the two members and a fluid-expansive diaphragm means disposed over the compression chamber and engaging both members, means to regulate the flow of a fluid pressure into the compression chamber to expand the diaphragm and produce jaw compression, and means to admit fluid pressure from the compression chamber 10 through the diaphragm to the spray chamber.

3. A press comprising, coacting jaws and operating means to move one of the jaws to open and close the press, one of the jaws 15 consisting of two relatively movable members and spring means to operatively hold them together, a spray chamber formed in one of the members, a compression chamber provided between the two members and a 20 fluid expansive diaphragm means disposed over the compression chamber and engaging both members, means to transmit fluid pressure into the compression chamber, said jaw being provided with a fluid passage from the spray chamber thru the diaphragm and into the compression chamber, and manually 25 operable valve means normally closing the fluid passage.

4. A press comprising, coacting jaws and 30 operating means to open and close the press, one of the jaws consisting of two relatively movable members and means to operatively hold them together, one member being provided with a heating chamber and the other 35 with a perforated spray chamber, a diaphragm disposed between and engaging both members and forming a compression chamber adjacent one member, and means to transmit fluid pressure from the heating chamber 40 into the compression chamber and from the latter thru the diaphragm into the spray chamber.

5. A press comprising, coacting jaws and operating means to open and close the press, 45 one of the jaws consisting of two relatively movable members and means to operatively hold them together, one member being provided with a heating chamber and the other with a perforated spray chamber, a dia- 50 phragm disposed between and engaging both members and forming a compression chamber adjacent one member, said dia- phragm and the other member being provided with a passage which opens into the com- 55 pression chamber, means to admit fluid pressure from the heating chamber to the compression chamber, and means to admit the fluid pressure from the compression chamber thru the passage to the spray chamber.

60 6. A press comprising, coacting jaws and operating means to open and close the press, one of the jaws consisting of two relatively movable members and means to operatively hold them together, one member being pro- 65 vided with a heating chamber and the other

with a perforated spray chamber, a circular flange formed on one member and proximate the heating chamber, a diaphragm having its periphery sealed to the flange thereby forming a fluid-expansive and compression chamber proximate the heating chamber and having engagement with the other member, valve means to regulate the flow of fluid pressure from the heating chamber into the compression chamber, and valve means to regulate the flow of fluid pressure from the compression chamber into the spray chamber. 70 75

7. A press comprising, coacting jaws and operating means to open and close the press, 80 one of the jaws consisting of a stationary member, a pressure plate and means movably mounting the same on the stationary member, a spray chamber provided in the pressure plate, a diaphragm placed between the member and plate and having its periphery sealed onto the stationary member and its center having operative connection with the pressure plate, compression control means carried on the jaw to regulate the flow of a fluid pressure against the diaphragm, said diaphragm being provided with a fluid opening which connects with the spray chamber, and spray control means carried on the jaw to regulate the flow of fluid pressure 85 thru the fluid opening in the diaphragm and into the spray chamber. 90 95

8. A press comprising, jaws and operating means to open and close the same, one of the jaws being provided with a heating chamber 100 into which steam is received to heat the jaw and spray the work, a pressure plate and means to attach it for relative movement on the chambered jaw, said pressure plate being provided with a perforated plate thru which to steam spray work spread upon the other jaw, a flexible disk-type corrugated circular diaphragm interposed between the pressure plate and chambered jaw and having its periphery and center secured to the chambered jaw and to the pressure plate which defines a compression chamber to receive fluid pressure to expand the diaphragm, a valve means connecting one side of the diaphragm to the heating chamber to admit 110 fluid pressure against the diaphragm, and a valve means interposed between the perforated plate and compression chamber to spray fluid pressure onto the work. 115 120

9. A press jaw comprising, a stationary member provided with a heating chamber, a pressure plate and means movably attaching it to the member, said heating chamber being curved away from the pressure plate along a portion of the jaw thereby affording a space between the pressure plate and stationary member, and fluid-pressure operated motor means concealed within the space and engaging the pressure plate to forcibly move 125 130

the latter in relation to the stationary member.

10. A press jaw comprising, a stationary member provided with a heating chamber, a pressure plate and means movably attaching it to the member, said heating chamber being curved away from the pressure plate along a portion of the jaw thereby affording a space between the pressure plate and jaw, fluid-pressure operated motor means concealed within the space and consisting of a flat circular and flexible diaphragm having its periphery sealed onto the stationary member and its center portion sealed onto the pressure plate to move the latter in relation to the member.

11. A press jaw comprising, a stationary member provided with a heating chamber, a pressure plate and means movably attaching it to the member, said heating chamber being curved away from the pressure plate along a portion of the jaw thereby affording a space between the pressure plate and jaw, a flat circular and flexible diaphragm mounted within the space and having its periphery sealed onto the stationary member and its center portion sealed onto the pressure plate to move the latter in relation to the member, a passage formed in the pressure plate thru the diaphragm, a spray chamber provided in the pressure plate and being connected with the passage, and valve means cooperating with the passage to open and close the same.

35 12. In a power press jaw for pressing machines, complementary members one of which is a compression plate and the other acting as a support for the compression plate and being provided with a fluid heating chamber, yieldable connecting means to hold the compression plate in intimate surface contact with a wall of the support containing the heating chamber by which the compression plate is heated by conductivity from the support, said jaw being provided with a space between the complementary members, and motor means mounted in the space and adapted to react from the support to move the compression plate with great force against the yieldable connecting means.

13. In a power press jaw, two complementary plate members having adjacent walls in intimate contact with each other, means to operatively connect the members together for relative motion, operating means between the members to move one in relation to the other, a flange formed on the margin of one member and overhanging the margin of the other whereby the latter moves within the flange and the latter acts to cover the space left at the plane of separation when relative motion occurs, and one of the members being provided with a heating chamber formed adjacent the plane of separation and the heat

from which passes through the adjacent contacting walls into the other member.

14. In a power press jaw, two complementary plate members having adjacent walls in intimate contact with each other, means to operatively connect the members together for relative motion, a flange formed on the margin of one member and overhanging the margin of the other whereby the latter moves within the flange and the flange acts to cover the space left at the plane of separation when relative motion occurs, one of the members being provided with a heating chamber formed adjacent the plane of separation and the heat from which passes through the adjacent contacting walls into the other member, said heating chamber having a substantially small portion thereof distorted away from the adjacent member thereby forming a space between the two members, and diaphragm means mounted in the space and operative to forcibly move one member on the other.

15. A press jaw as defined in claim 14 but characterized by means to feed fluid pressure from the heating chamber to the diaphragm means to expand the same.

16. A press jaw as defined in claim 14 but characterized by a spray chamber being formed in the member opposite the one containing the heating chamber, and means to convey a heating fluid from the heating chamber through the space into the spray chamber.

17. In a press jaw, a support and a compression plate movably carried thereon, said compression plate being provided with a spray chamber, said support being provided with a fluid expansion space and a flat-disk diaphragm having its rim sealed thereto and forming a closed expansion chamber and reacting from the support to actuate the compression plate, said pressing jaw being provided with a passage extending from the fluid expansion chamber to the spray chamber to transmit fluid from the former to the latter, and a control valve mounted in the passage whereby fluid pressure is discharged into the spray chamber.

18. In a press jaw, a support and a compression plate movably carried thereon, said plate having a spray chamber, said support having a space therein formed and a diaphragm mounted in the space with its rim sealed to said support thereby forming a fluid expansion chamber, means sealing the center of the diaphragm to the plate, a passage formed through the center of the diaphragm and through the plate into the spray chamber, and a valve mounted in the passage to discharge fluid from the expansion chamber into the spray chamber.

19. In a press jaw, two members one being a support and the other a presser plate movably mounted thereon and each of which is

- 6
- provided with a fluid chamber, a diaphragm disposed between the two members, means sealing the center of the diaphragm to one member and the periphery thereof to the other member, a passage through one member and through the diaphragm connecting the fluid chambers of the members, and a valve in the passage to control the flow of fluid therethrough.
- 5 10 In testimony whereof I affix my signature.
